ENVELOPE MACHINE

Arthur L. Roloff, Chicago, Ill., assignor to Garden City Envelope Co., Chicago, Ill., a corporation of Illinois

Application January 3, 1938, Serial No. 182,968

5 Claims. (Cl. 93—62)

My invention relates to envelope machines. For certain purposes, it has been found desirable to provide envelopes with a binding strip which can readily be bound in with the pages of a magazine, or the like, and in which the envelope itself can be readily detached from the magazine and mailed to an address which may be already provided on the envelope. This use of envelopes make necessary a binding strip, by means of which the envelope may be secured in the magazine, from which binding strip the envelope is torn off for mailing purposes, leaving the binding strip in the magazine, a weakened line generally being provided between this binding strip and the envelope proper. This type of envelope has created a problem in production.

One of the objects of my invention is to provide an improved apparatus for making such an envelope.

Other objects and advantages of the invention will be apparent from the description and claims.

In the drawings, in which an embodiment of my invention is shown,—

Figure 1 is a plan view showing successive steps in the formation of an envelope as it passes through my improved apparatus;

Fig. 2 is a side elevational view showing diagrammatically the apparatus used in performing the steps shown in Fig. 1;

Fig. 3 is a vertical, sectional, elevational view showing diagrammatically the rear end of the machine;

Fig. 4 is an enlarged view showing the gripper removing the envelopes from the conveyor;

Fig. 5 is a bottom view of parts of Fig. 4 showing the gripper removing the envelope from the conveyor;

Fig. 6 is a vertical sectional view showing the perforating and shearing cutters;

Fig. 7 is a section on the line 7—7 of Fig. 6;

Fig. 8 is a section on the line 8—8 of Fig. 6;

Fig. 9 is a view showing the finished envelope secured in place on a magazine page.

Before describing the apparatus, I will briefly describe the envelope formed by the apparatus. The blank from which this envelope is formed is shown at stage A in Figs. 1, 2, and 5 and comprises a rectangular central portion 1 bounded by scored and perforated lines 2 and 3, as indicated, a side edge flap 4 which is finally folded over as shown at stage D, Fig. 1, a bottom edge flap 5 which is finally folded over and secured to the gummed parts 6, stage F, on the envelope, as indicated at stage G, a closing flap 7 having a gummed part 8 for sealing the envelope, all of

said flaps extending from said rectangular central portion 1, a binding strip 9 extending laterally from the central portion 1 and the closing flap 7 to provide a strip which may be secured to the edge of the magazine page 10, as shown in Fig. 9, and a wing portion 11 extending laterally from the binding strip portion. This wing portion 11 is sheared off at stage E, in Fig. 1, from the envelope proper and discarded after it has served its purpose of providing an edge in feeding the envelope through the apparatus. This shearing-off step is performed at the same time that the weakened or perforated line 3 is formed in the envelope. This weakened line enables the envelope to be readily detached from the binding strip 9 when it is desired to mail the envelope.

The wing portion 11, which I have described as finally sheared off from the envelope proper after it has served its purpose, provides a shoulder portion 12 which cooperates with an aligning pin 13 (Figs. 1 and 2, stage B) on the conveyor 14, the side edge flap 4 also providing a shoulder 15 which cooperates with an opposed aligning pin 13 on the conveyor, so that by means of these two shoulder portions 12 and 15 the aligning pins 13 on the chain conveyor can properly engage the envelope to feed it to the creasing rolls 16 (Figs. 1 and 2, stage C), which form the creases 2 bounding the rectangular central portion 1 of the envelope blank. This wing portion 11 also provides an extension which cooperates with the gripping clips 17 on the conveyor chain 18 (Figs. 4 and 5), the clips 17 of one of the chains 18 gripping the rear edges of the wing portions 11, respectively, and the gripping clips 17 of the opposite chain 18 engaging the rear edges of the side flaps 4.

As the envelopes are carried along by the conveyor chains 18, they pass up over the roller 19 (Figs. 3 and 4) and are delivered to the gripping rollers 20 (Fig. 2, stage A), which are rotating at a relatively high speed so that these gripping rollers will seize the envelopes successively as they are fed thereto by the conveyor chains 18 and will move the envelopes forward at such a rapid rate that they will be taken away from the gripping clips 17 on the chains, as shown in Fig. 4, and will be fed to the creasing rolls 16. The passage of the chains 18 around the sprockets 21 causes the clips 17 to release the envelopes to enable them to be readily removed by the gripping rolls 20. The gripping rolls feed the envelopes into position where they can be engaged by the aligning pins 13 on the conveyor 14 (Figs. 1 and 2, stage B). These aligning pins straighten up

the envelope if it is out of alignment and feed it to the creasing rolls 16 (stage C). From the creasing rolls, the envelopes are fed to the "plow-share" 22 (Figs. 1 and 2, stage D), which folds over the side edge flap 4 and presses it down onto the rectangular central portion 1. From this "plowshare" folder 22 the envelopes are fed to stage E (Figs. 1 and 2) where the feed rollers 23 and 24 (Fig. 6) carry the envelopes between the overlapping rotating cutters 25 and 26. These cutters 25 and 26 shear off the wing portion 11 which has now served its purpose. At the same time the envelope is being carried underneath a perforating cutter 27 which cooperates with a platen roller 28 to the weakened line 3 in the envelope blank so that when the binding strip 8 is secured to the magazine page 10, the envelope proper can be readily detached, leaving the binding strip 8 in the magazine. After the wing portion 11 has been sheared off and the weakened line 3 formed between the binding strip 8 and the body of the envelope, the blank is passed beneath glue-applying rollers 29 which apply adhesive to the envelope blank, as indicated at 6 (Figs. 1 and 2, stage F). Thereafter the blanks are fed to the flap-folding apparatus (Figs. 1 and 2, stage G), which folds the bottom flap 5 over on top of the gummed portions 6 of the envelope so that the envelope finally appears as shown at the right hand of Fig. 1. The envelope is now ready to be stitched in or otherwise secured in position in the magazine.

It will be noted that the provision of the wing portion 11, which is sheared off after it has served its purpose, enables the envelope blanks to be handled by the chain conveyor 18 and by the aligning pins 13 so that the blanks can be used in a continuous rotary type envelope machine. No claim is made to any novelty in the aligning pin conveyor 14 and the chain clip conveyor 18 per se, or in the gumming and folding mechanism per se, as specific apparatus of the general type shown in Patent Nos. 1,396,906; 1,734,742; 1,807,863; 1,807,867, and 1,827,539.

Referring more in detail to the shearing and perforating part of the apparatus shown in Figs. 6, 7, and 8, this comprises a pair of parallel spaced shafts 30 and 31, geared together by means of spur gears 32 and 33 and driven in any suitable manner at proper speed, the feed rolls 23 and 24 for feeding the envelopes through the shearing and perforating apparatus, the shearing disc 25 rotatable with the lower shaft 31, the shearing disc 26 rotatable with the upper shaft 30, and the platen roller 28 toward which the lower edge of the perforating disc 27 is urged (the perforating being done by the cooperation of the edge of the perforating disc 27 with the opposed platen 28), and a pair of aligning discs 35 and 36, the lower one 35 being mounted on the lower shaft 31 and having a groove 37 into which the outer edge of the upper disc 36 fits nicely, and this upper disc being secured to rotate with the upper shaft 30. It will be seen that these two discs will hold the two shafts against relative endwise play so that the proper alignment of the upper shearing disc 25 and the perforating wheel 27 with respect to the lower shearing disc 26 and platen 28 is preserved.

The shearing disc 25 may be held in properly adjusted position on the threaded sleeve 38, which

is secured to rotate with the upper shaft, by means of a pair of nuts 39 and 40 threaded on this sleeve 38, these nuts being secured in the desired adjusted position by means of set screws 41 which are threaded in the lock nuts and the tips of which may engage the threaded sleeve 38. The coil compression springs 34 which hold the upper shearing disc against the lower shearing disc may be seated in suitable pockets in the nut 39. In a similar manner the perforating disc 27 is held in any desired position of axial adjustment on the threaded sleeve 38 by means of nuts 42 and 43, which may be secured in position by means of set screws 41.

In order to direct the sheared-off wing 11 downwardly so that it will not get caught in the machinery, a deflecting guide 44 (Fig. 2) may be provided which will engage the upper side of the wing portion 11 as it is sheared off and direct it downwardly out of the way. In order to secure the proper contact between the perforating cutter 27 and its cooperating platen 28, the cutter is made so that it can have a slight floating movement with respect to the sleeve 38 on which it is mounted, the construction being such that the perforating edge 45 will be urged frictionally toward the cooperating platen 28 to secure just the right degree of pressure between the perforating edge and the platen. The perforating edge may be serrated, as shown in Fig. 8, to secure the proper perforating effect on the envelope. This floating action of the cutter 27 is secured by making the opening 46 in the cutter slightly larger in diameter than the outside diameter of the threaded sleeve 38 and providing a slip friction drive for the perforating cutter. This slip friction drive is effected by means of a washer 47 of suitable material, such as leather, or the like, and a second washer 48, which may be of any suitable material, such as brass, located between this leather washer 47 and the face of the perforating disc 27. The lock nuts 42 and 43 are so adjusted that the leather washer 47 will cause the desired degree of pressure to be exerted by the brass washer 48 on the perforating disc 27. As the envelope passes between the platen 28 and the perforating cutter 27, it will tend to force the perforating cutter 27 upwardly slightly so that the cutter will be eccentric with respect to the axis of the rotating shaft 30. This eccentricity will cause the serrated edge 45 of the perforating cutter to become eccentric with respect to the axis of the shaft 30. Thus, the distance of the upper edge of the perforating disc 27 from the axis of the shaft 30 will tend to be greater than the distance of the lower edge of the perforating disc from the axis of the shaft. As the perforating disc rotates, portions of the perforating edge, gradually increasing in distance from the axis of the shaft, will be rotating toward the point of contact between the perforating edge 45 and the envelope and this will cause a constant shifting of the perforating disc 27 with respect to the axis of the shaft 30 on which it is mounted. The large opening in the perforating disc 27 and the frictional mounting effected by the washers 47 and 48 enable this shifting of the perforating disc with respect to its axis. By properly tensioning the friction disc, just the required degree of pressure of the perforating disc on the envelope may be secured.

In order to guide the envelope in its movement between the shearing discs 25 and 26 and underneath the perforating cutter 27, a suitable guide wire 49 may be provided, the lower portion 75

of which engages the upper face of the envelope as it travels.

It will be seen that by the use of my improved blank and the apparatus cooperating therewith envelopes of the type desired to be detachably secured in a magazine may be produced by a continuous method involving the use of rotary creasing wheels, rotary cutting and perforating discs, and rotary gum-applying apparatus.

10 In the claims, where I have used the word "mutilate", it is to be understood as being broad enough to cover shearing, cutting, perforating, and the like.

Further modifications will be apparent to those skilled in the art and it is desired, therefore, that the invention be limited only by the prior art and the scope of the appended claims.

Having thus described my invention, what I claim and desire to secure by Letters Patent is:

20 1. An envelope machine for forming an envelope from a blank, which blank comprises a rectangular central portion, a side edge flap, a bottom edge flap, and a closing flap, all of said flaps extending from said central portion, a binding strip extending laterally from said central portion and closing flap, and a wing portion extending laterally from said binding strip, said machine comprising conveyor means for the blanks engaging said side edge flap and said 25 wing portion, means for folding said side edge flap onto said central portion, and means for forming a weakened line between said central portion and said binding strip.

2. An envelope machine for forming an envelope from a blank, which blank comprises a rectangular central portion, a side edge flap, a bottom edge flap, and a closing flap, all of said flaps extending from said central portion, a binding strip extending laterally from said central portion and closing flap, and a wing portion extending laterally from said binding strip, said machine comprising conveyor means for the blanks engaging said side edge flap and said wing portion, means for folding said side 30 flap onto said central portion, and means for severing said wing portion from said binding strip.

30 3. An envelope machine for forming an envelope from a blank, which blank comprises a

rectangular central portion, a side edge flap, a bottom edge flap, and a closing flap, all of said flaps extending from said central portion, a binding strip extending laterally from said central portion and closing flap, and a wing portion extending laterally from said binding strip, said machine comprising conveyor means for the blanks engaging said side edge flap and said wing portion, means for folding said side edge flap onto said central portion, and rotatable 10 means for forming a weakened line between said central portion and said binding strip.

4. An envelope machine for forming an envelope from a blank, which blank comprises a rectangular central portion, a side edge flap, a bottom edge flap, and a closing flap, all of said flaps extending from said central portion, a binding strip extending laterally from said central portion and closing flap, and a wing portion extending laterally from said binding strip, said 15 machine comprising conveyor means for the blanks engaging said side edge flap and said wing portion, means for folding said side edge flap onto said central portion, rotatable means for forming a weakened line between said central portion and said binding strip, and rotatable means coaxial with said first rotatable means for severing said wing portion from said binding strip.

5. An envelope machine for forming an envelope from a blank, which blank comprises a rectangular central portion, a side edge flap, a bottom edge flap, and a closing flap, all of said flaps extending from said central portion, a binding strip extending laterally from said central portion and closing flap, and a wing portion extending laterally from said binding strip, said machine comprising conveyor means for the blanks engaging said side edge flap and said wing portion, means for folding said side 30 edge flap onto said central portion, and means for forming a weakened line between said central portion and said binding strip comprising a rotor having a circular sheet-mutilating edge, a rotor having a circular platen edge cooperating with said mutilating edge, a rotatable shaft, one of said rotors being mounted on said shaft for a limited radial movement with respect to said shaft, and friction means for resisting said radial movement.

ARTHUR L. ROLOFF.
